(57) **ABSTRACT**

Discrimination between at least two classes of events in an input signal is carried out in the following way. A set of frames containing an input signal is received, and at least two different feature vectors are determined for each of said frames. Said at least two different feature vectors are classified using respective sets of preclassifiers trained for said at least two classes of events. Values for at least one weighting factor are determined based on outputs of said preclassifiers for each of said frames. A combined feature vector is calculated for each of said frames by applying said at least one weighting factor to said at least two different feature vectors. Said combined feature vector is classified using a set of classifiers trained for said at least two classes of events.

VOICE ACTIVITY DETECTION SYSTEM
AND METHOD

BACKGROUND

1. Field

Embodiments of the invention relates in general to voice activity detection, and more specifically, to discriminating between event types, such as speech and noise.

2. Background

Voice activity detection (VAD) is an essential part in many speech processing tasks such as speech coding, hands-free telephony and speech recognition. For example, in mobile communication the transmission bandwidth over the wireless interface is considerably reduced when the mobile device detects the absence of speech. A second example is automatic speech recognition system (ASR). VAD is important in ASR, because of restrictions regarding memory and accuracy. Inaccurate detection of the speech boundaries causes serious problems such as degradation of recognition performance and deterioration of speech quality.

VAD has attracted significant interest in speech recognition. In general, two major approaches are used for designing such a system: threshold comparison techniques and model based techniques. For the threshold comparison approach, a variety of features like, for example, energy, zero crossing, autocorrelations coefficients, etc. are extracted from the input signal and then compared against some thresholds. Some approaches can be found in the following publications: Li, Q., Zheng, J., Zhou, Q., and Lee, C.-H., "A robust, real-time endpoint detector with energy normalization for ASR in adverse environments," *Proc. ICASSP*, pp. 233-236, 2001; L. R. Rabiner, et al., "Application of an LPC Distance Measure to the Voiced-Unvoiced-Silence Detection Problem," *IEEE Trans. On ASSP*, vol. ASSP-25, no. 4, pp. 338-343, August 1977.

The thresholds are usually estimated from noise-only and updated dynamically. By using adaptive thresholds or appropriate filtering their performance can be improved. See, for example, Martin, A., Charlet, D., and Mauuary, L, "Robust Speech/Nonspeech Detection Using LDA applied to MFCC," *Proc. ICASSP*, pp. 237-240, 2001; Monkowski, M., *Automatic Gain Control in a Speech Recognition System*, U.S. Pat. No. 6,314,396; and Lie Lu, Hong-Jiang Zhang, H. Jiang, "Content Analysis for Audio Classification and Segmentation," *IEEE Trans. Speech & Audio Processing*, Vol. 10, N0.7, pp. 504-516, October 2002.

Alternatively, model based VAD were widely introduced to reliably distinguish speech from other complex environment sounds. Some approaches can be found in the following publications: J. Ajmera, I. McCowan, "Speech/Music Discrimination Using Entropy and Dynamism Features in a HMM Classification Framework," *IDIAP-RR 01-26*, IDIAP, Martigny, Switzerland 2001; and T. Hain, S. Johnson, A. Tuerk, P. Woodland, S. Young, "Segment Generation and Clustering in the HTK Broadcast News Transcription System", *DARPA Broadcast News Transcription und Understanding Workshop*, pp. 133-137, 1998. Features such us full band energy, sub-band energy, linear prediction residual energy or frequency based features like Mel Frequency Cepstral Coefficients (MFCC) are usually employed in such systems.

Threshold adaptation and energy features based VAD techniques fail to handle complex acoustic situations encountered in many real life applications where the signal energy level is usually highly dynamic and background sounds such as music and non-stationary noise are common. As a consequence, noise events are often recognized as words causing

insertion errors while speech events corrupted by the neighbouring noise events cause substitution errors. Model based VAD techniques work better in noisy conditions, but their dependency on one single language (since they encode phoneme level information) reduces their functionality considerably.

The environment type plays an important role in VAD accuracy. For instance, in a car environment where high signal to noisy ratio (SNR) conditions are commonly encountered when the car is stationary an accurate detection is possible. Voice activity detection remains a challenging problem when the SNR is very low and it is common to have high intensity semi-stationary background noise from the car engine and high transient noises such as road bumps, wiper noise, door slams. Also in other situations, where the SNR is low and there is background noise and high transient noises, voice activity detection is challenging.

It is therefore highly desirable to develop a VAD method/system which performs well for various environments and where robustness and accuracy are important considerations.

SUMMARY

It is an aim of embodiments of the present invention to address one or more of the problems discussed above.

According to a first aspect of an embodiment the present invention there is provided a computerized method for discriminating between at least two classes of events, the method comprising the steps of:

30 receiving a set of frames containing an input signal,
determining at least two different feature vectors for each
of said frames,
classifying said at least two different feature vectors using
respective sets of preclassifiers trained for said at least
two classes of events,
determining values for at least one weighting factor based
on outputs of said preclassifiers for each of said frames,
calculating a combined feature vector for each of said
frames by applying said at least one weighting factor to
said at least two different feature vectors, and
classifying said combined feature vector using a set of
classifiers trained for said at least two classes of events.

The computerised method may comprise determining at

45 least one distance between outputs of each of said sets of
preclassifiers, and determining values for said at least one
weighting factor based on said at least one distance.

The method may further comprise comparing said at least
one distance to at least one predefined threshold, and calcu-
lating values for said at least one weighting factor using a
50 formula dependent on said comparison. Said formula may use
at least one of said at least one threshold values as input.

The at least one distance may be based on at least one of the
55 following: Kullback-Leibler distance, Mahalanobis distance,
and Euclidian distance.

An energy-based feature vector may be determined for
each of said frames. Said energy-based feature vector may be
based on at least one of the following: energy in different
frequency bands, log energy, and speech energy contour.

A model-based feature vector may be determined for each
60 of said frames. Said model-based technique may be based on
at least one of the following: an acoustic model, neural net-
works, and hybrid neural networks and hidden Markow
model scheme.

In one specific embodiment, a first feature vector based on
65 energy in different frequency bands and a second feature
vector based on an acoustic model is determined for each of
said frames. Said acoustic model in this specific embodiment

may be one of the following: a monolingual acoustic model, and a multilingual acoustic model.

A second aspect of an embodiment of an embodiment of the present invention provides a computerized method for training a voice activity detection system, comprising receiving a set of frames containing a training signal, determining quality factor for each of said frames, labelling said frames into at least two classes of events based on the content of the training signal, determining at least two different feature vectors for each of said frames, training respective sets of preclassifiers to classify said at least two different feature vectors using for said at least two classes of events, determining values for at least one weighting factor based on outputs of said preclassifiers for each of said frames, calculating a combined feature vector for each of said frames by applying said at least one weighting factor to said at least two different feature vectors, and classifying said combined feature vector using a set of classifiers to classify said combined feature vector into said at least two classes of events.

The method may comprise determining thresholds for distances between outputs of said preclassifiers for determining values for said at least one weighting factor.

A third aspect of the invention provides a voice activity detection system for discriminating between at least two classes of events, the system comprising:

feature vector units for determining at least two different feature vectors for each frame of a set of frames containing an input signal, sets of preclassifiers trained for said at least two classes of events for classifying said at least two different feature vectors, a weighting factor value calculator for determining values for at least one weighting factor based on outputs of said preclassifiers for each of said frames, a combined feature vector calculator for calculating a value for the combined feature vector for each of said frames by applying said at least one weighting factor to said at least two different feature vectors, and a set of classifiers trained for said at least two classes of events for classifying said combined feature vector.

In the voice activity detection system, said weighting factor value calculator may comprise thresholds for distances between outputs of said preclassifiers for determining values for said at least one weighting factor.

A further aspect of the invention provides a computer program product comprising a computer-readable medium and a computer readable program, wherein the computer readable program when executed on a data processing system causes the data processing system to carry out method steps as described above.

BRIEF DESCRIPTION OF FIGURES

For a better understanding of embodiments of the present invention and as how the same may be carried into effect, reference will now be made by way of example only to the accompanying drawings in which:

FIG. 1 shows schematically, as an example, a voice activity detection system in accordance with an embodiment of the invention;

FIG. 2 shows, as an example, a flowchart of a voice activity detection method in accordance with an embodiment of the invention;

FIG. 3 shows schematically one example of training a voice activity detection system in accordance with an embodiment of the invention; and

FIG. 4 shows schematically a further example of training a voice activity detection system in accordance with an embodiment of the invention.

DETAILED DESCRIPTION

10 Embodiments of the present invention combine a model based voice activity detection technique with a voice activity detection technique based on signal energy on different frequency bands. This combination provides robustness to environmental changes, since information provided by signal energy in different energy bands and by an acoustic model complements each other. The two types of feature vectors obtained from the signal energy and acoustic model follow the environmental changes. Furthermore, the voice activity detection technique presented here uses a dynamic weighting factor, which reflects the environment associated with the input signal. By combining the two types of feature vectors with such a dynamic weighting factor, the voice activity detection technique adapts to the environment changes. Although feature vectors based on acoustic model and energy in different frequency bands are discussed in detail below as a concrete example, any other feature vector types may be used, as long as the feature vector types are different from each other and they provide complement information on the input signal.

15 20 25 30 35 40 45 50

A simple and effective feature for speech detection in high SNR conditions is signal energy. Any robust mechanism based on energy must adapt to the relative signal and noise levels and the overall gain of the signal. Moreover, since the information conveyed in different frequency bands is different depending on the type of phonemes (sonorant, fricatives, glides, etc) energy bands are used to compute these features type. A feature vector with m components can be written like $(E_{n_1}, E_{n_2}, E_{n_3}, \dots, E_{n_m})$, where m represents the number of bands. A feature vector based on signal energy is the first type of feature vectors used in voice activity detection systems in accordance with embodiments of the present invention. Other feature vector types based on energy are spectral amplitude, such as log energy and speech energy contour. In principle, any feature vector which is sensitive to noise can be used.

Frequency based speech features, like mel frequency cepstral coefficients (MFCC) and their derivatives, Perceptual Linear Predictive coefficients (PLP), are known to be very effective to achieve improved robustness to noise in speech recognition systems. Unfortunately, they are not so effective for discriminating speech from other environmental sounds when they are directly used in a VAD system. Therefore a way of employing them in a VAD system is through an acoustic model (AM).

When an acoustic model is used, the functionality of the 55 VAD typically limited only to that language for which the AM has been trained. The use of a feature based VAD for another language may require a new AM and re-training of the whole VAD system at increased cost of computation. It is thus advantageous to use an AM trained on a common phonology which is able to handle more than one language. This minimizes the effort at a low cost of accuracy.

A multilingual AM requires speech transcription based on a common alphabet across all the languages. To reach a common alphabet one can start from the previous existing alphabets for each of the involved languages where some of them need to be simplify and then to merge phones present in several languages that correspond to the same IPA symbol.

This approach is discussed in F. Palou Cambra, P. Bravetti, O. Emam, V. Fischer, and E. Janke, "Towards a common alphabet for multilingual speech recognition," in *Proc. of the 6th Int. Conf. on Spoken Language Processing*, Beijing, 2000. Acoustic modelling for multilingual speech recognition to a large extend makes use of well established methods for (semi-) continuous Hidden-Markov-Model training, but a neural network which will produce the posterior class probability for each class can also be taken into consideration for this task. This approach is discussed in V. Fischer, J. Gonzalez, E. Janke, M. Villani, and C. Waast-Richard, "Towards Multilingual Acoustic Modeling for Large Vocabulary Continuous Speech Recognition," in *Proc. of the IEEE Workshop on Multilingual Speech Communications*, Kyoto, Japan, 2000; S. Kunzmann, V. Fischer, J. Gonzalez, O. Emam, C. Günther, and E. Janke, "Multilingual Acoustic Models for Speech Recognition and Synthesis," in *Proc. of the IEEE Int. Conference on Acoustics, Speech, and Signal Processing*, Montreal, 2004.

Assuming that both speech and noise observations can be characterized by individual distributions of Gaussian mixture density functions, a VAD system can also benefit from an existing speech recognition system where the statistic AM is modeled as a Gaussian Model Mixtures (GMM) within the hidden Markov model framework. An example can be found in "E. Marchet, K. Visweswariah, G. Potamianos, "Speech Activity Detection fusing Acoustic Phonetic and Energy Features," Proc./ICASLP 2005. Each class posterior probabilities for speech/noise events are computed on a frame basis and called within this invention as (P₁, P₂). They represent the second type of feature vector (FV).

In the following description, a multilingual acoustic model is often used as an example of a model providing feature vectors. It is appreciated that it is straightforward to derive a monolingual acoustic model from a multilingual acoustic model. Furthermore, it is possible to use a specific monolingual acoustic model in a voice detection system in accordance with an embodiment of the invention.

The first feature vectors (En₁, En₂, En₃, ..., En_m) relating to the energy of frequency bands are input to a first set of pre-classifiers. The second feature vectors, for example (P₁, P₂) for the two event types, provided by an acoustic model or other relevant model are input into a second set of pre-classifiers. The pre-classifiers are typically Gaussian mixture pre-classifiers, outputting Gaussian mixture distributions. For any of the Gaussian Mixture Models employed in embodiments of this invention, one can use for instance neural networks to estimate the posterior probabilities of each of the classes.

The number of pre-classifiers in these sets corresponds with the number of event classes the voice activity detection system needs to detect. Typically, there are two event classes: speech and non-speech (or, in other words, speech and noise). But depending on the application, there may be need for a larger number of event classes. A quite common example is to have the following three event classes: speech, noise and silence. The pre-classifiers have been trained for the respective event classes. Training is discussed in some detail below.

At high SNR (clean environment) the distributions of the two classes are well separated and any of the pre-classifiers associated with the energy based models will provide a reliable output. It is also expected that the classification models associated with the (multilingual) acoustic model will provide a reasonably good class separation. At low SNR (noisy environment) the distributions of the two classes associated

with the energy bands overlap considerably making questionable the decision based on the pre-classifiers associated with energy bands alone.

It seems that one of the FV type is more effective than the other depending on the environment type (noisy or clean). But in real applications changes in environment occur very often requiring the presence of both FV types in order to increase the robustness of the voice activity detection system to these changes. Therefore a scheme where the two FV types are weighted dynamically depending on the type of the environment will be used in embodiments of the invention.

There remains the problem of defining the environment in order to decide which of the FV will provide the most reliable decision. A simple and effective way of inferring the type of the environment involves computing distances between the event type distributions, for example between the speech/noise distributions. Highly discriminative feature vectors which provide better discriminative classes and lead to large distances between the distributions are emphasized against the feature vectors which no dot differentiate between the distributions so well. Based on the distances between the models of the pre-classifiers, a value for the weighting factor is determined.

FIG. 1 shows schematically a voice activity detection system 100 in accordance with an embodiment of the invention. FIG. 2 shows a flowchart of the voice activity detection method 200. It is appreciated that the order of the steps in the method 200 may be varied. Also the arrangement of blocks may be varied from that shown in FIG. 1, as long as the functionality provided by the block is present in the voice detection system 100.

The voice activity detection system 100 receives input data 101 (step 201). The input data is typically split into frames, which are overlapping consecutive segments of speech (input signal) of sizes varying between 10-30 ms. The signal energy block 104 determines for each frame a first feature vector, (En₁, En₂, En₃, ..., En_m) (step 202). The front end 102 calculates typically for each frame MFCC coefficients and their derivatives, or perceptual linear predictive (PLP) coefficients (step 204). These coefficients are input to an acoustic model AM 103. In FIG. 1, the acoustic model is, by the way of example, shown to be a multilingual acoustic model. The acoustic model 103 provides phonetic acoustic likelihoods as a second feature vector for each frame (step 205). A multilingual acoustic model ensures the usage of a model dependent VAD at least for any of the language for which it has been trained.

The first feature vectors (En₁, En₂, En₃, ..., En_m) provided by the energy band block 104 are input are input to a first set of pre-classifiers M3, M4 121, 122 (step 203). The second feature vectors (P1, P2) provided by the acoustic model 103 are input into a second set of pre-classifiers M1, M2 111, 112 (step 206). The pre-classifiers M1, M2, M3, M4 are typically Gaussian mixture pre-classifiers, outputting Gaussian mixture distributions. A neural network can be also used to provide the posterior probabilities of each of the classes. The number of pre-classifiers in these sets corresponds with the number of event classes the voice activity detection system 100 needs to detect. FIG. 1 shows the event classes speech/noise as an example. But depending on the application, there may be need for a larger number of event classes. The pre-classifiers have been trained for the respective event classes. In the example in FIG. 1, M₁ is the speech model trained only with (P₁, P₂), M₂ is the noise model trained only with (P₁, P₂), M₃ is the speech model trained only with (En₁, En₂, En₃ ..., En_m) and M₄ is the noise model trained only with (En₁, En₂, En₃ ..., En_m).

The voice activity detection system **100** calculates the distances between the distributions output by the pre-classifiers in each set (step **207**). In other words, a distance **KL12** between the outputs of the pre-classifiers **M1** and **M2** is calculated and, similarly, a distance **KL34** between the outputs of the pre-classifiers **M3** and **M4**. If there are more than two classes of event types, distances can be calculated between all pairs of pre-classifiers in a set or, alternatively, only between some predetermined pairs of pre-classifiers. The distances may be, for example, Kullback-Leibler distances, Mahalanobis distances, or Euclidian distances. Typically same distance type is used for both sets of pre-classifiers.

The VAD system **100** combines the feature vectors (P_1, P_2) and ($En_1, En_2, En_3 \dots En_m$) into a combined feature vector by applying a weighting factor k on the feature vectors (step **209**). The combined feature vector can be, for example, of the following form:

$$(k*En_1 k*En_2 k*En_3 \dots k*En_m (1-k)*P_1 (1-k)*P_2).$$

A value for the weighting factor k is determined based on the distances **KL12** and **KL34** (step **208**). One example of determined the value for the weighting factor k is the following. During the training phase, when the SNR of the training signal can be computed, a data structure is formed containing SNR class labels and corresponding **KL12** and **KL34** distances. Table 1 is an example of such a data structure.

pair is computed. The environment type is computed at the training phase for each frame and the corresponding **KL** distances are collected into the look up table (Table 1). At run time, when the information about the SNR is missing, for each speech frame one computes distance values **KL12** and **KL34**. Based on comparison of **KL12** and **KL34** values against the corresponding threshold values in the look up table, one retrieves the information about SNR type. In this way the type of environment (SNR class) can be retrieved.

As a summary, the values in Table 1 or in a similar data structure are collected during the training phase, and the thresholds are determined during the training phase. In the run-time phase, when voice activity detection is carried out, the distance values **KL12** and **KL34** are compared to the thresholds in Table 1 (or in the similar data structure), and based on the comparison it is determined which SNR class describing the environment of the current frame.

After determining the current environment (SNR range), the value for the weighting factor can be determined based on the environment type, for example, based on the threshold values themselves using the following relations.

1. for $SNR < THRESHOLD_1$, $k = \min(TH_{12L}, TH_{34L})$,
2. for $SNR > THRESHOLD_1$, $k = \max(TH_{12H}, TH_{34H})$

As an alternative to using the threshold values in the calculation of the weighting factor value, the distance values **KL12** and **KL34** can be used. For example, the value for k can

TABLE 1

High			KL _{12H-frame-n+1}	KL _{34H-frame-n+1}	
High			KL _{12H-frame-n+2}	KL _{34H-frame-n+2}	
High			KL _{12H-frame-n+3}	KL _{34H-frame-n+3}	
...	...	...	...	...	...
High			KL _{12H-frame-n+m}	KL _{34H-frame-n+m}	

As Table 1 shows, there may be threshold values that divide the SNR space into ranges. In Table 1, threshold value **THRESHOLD₁** divide the SNR space into two ranges: low SNR, and high SNR. The distance values **KL12** and **KL34** are used to predict the current environment type and are computed for each input speech frame (e.g. 10 ms).

In Table 1, there is one column for each SNR class and distance pair. In other words, in the specific example here, there are two columns (SNR high, SNR low) for distance **KL12** and two columns (SNR high, SNR low) for distance **KL34**. As a further option to the format of Table 1, it is possible during the training phase to collect all distance values **KL12** to one column and all distance values **KL34** to a further column. It is possible to make the distinction between SNR low/high by the entries in the SNR class column.

Referring back to the training phase and Table 1, at the frame x if the environment is noisy (low SNR) only ($KL_{12L-frame-x}$ and $KL_{34L-frame-x}$) pair will be computed. At the next frame ($x+1$), if the environment is still noisy, ($KL_{12L-frame-x+1}$ and $KL_{34L-frame-x+1}$) pair will be computed otherwise (high SNR) ($KL_{12H-frame-x+1}$ and $KL_{34H-frame-x+1}$)

be $k = \min(KL12, KL34)$, when $SNR < THRESHOLD1$, and $k = \max(KL12, KL34)$, when $SNR > THRESHOLD1$. This way the voice activity detection system is even more dynamic in taking into account changes in the environment.

The combined feature vector (Weighted FV*) is input to a set of classifiers **131**, **132** (step **210**), which have been trained for speech and noise. If there are more than two event types, the number of pre-classifier and classifiers in the set of classifiers acting on the combined feature vector will be in line with the number of event types. The set of classifiers for the combined feature vector typically uses heuristic decision rules, Gaussian mixture models, perceptron, support vector machine or other neural networks. The score provided by the classifiers **131** and **132** is typically smoothed over a couple of frames (step **211**). The voice activity detection system then decides on the event type based on the smoothed scores (step **212**).

FIG. 3 shows schematically training of the voice activity detection system **100**. Preferably, training of the voice activity detection system **100** occurs automatically, by inputting a training signal **301** and switching the system **100** into a train-

11

It is furthermore possible to have more than two event classes. In this case there are more pre-classifiers and classifiers in the voice activity detection system. For example, for three event classes (speech, noise, silence), three distances are considered: $KL(\text{speech, noise})$, $KL(\text{speech, silence})$ and $KL(\text{noise, silence})$. FIG. 4 shows, as an example, training phase of a voice activity detection system, where there are three event classes and two SNR classes (environments type). There are three pre-classifiers (that is, the number of the event classes) for each feature vector type, namely models 111, 112, 113 and models 121, 122, 123. In FIG. 4, the number of distances monitored during the training phase is 6 for each feature vector type, for example KL_{12H} , KL_{12L} , KL_{13H} , KL_{13L} , KL_{23H} , KL_{23L} for the feature vector obtained from the acoustic model. The weight factor between the FVs depends on the SNR and FV's type. Therefore, if the number of defined SNR classes and the number of feature vectors remains unchanged, the procedure of weighting remains also unchanged. If the third SNR class is medium, a maximum value of 0.5 for the energy type FV is recommended but depending on the application it might be slightly adjusted.

It is furthermore feasible to have more than two feature vectors for a frame. The final weighted FV be of the form: $(k_1 * FV1, k_2 * FV2, k_3 * FV3, \dots, k_n * FVn)$, where $k_1+k_2+k_3+\dots+k_n=1$. What needs to be taken into account by using more FVs is their behaviour with respect to different SNR classes. So, the number of SNR classes could influence the choice of FV. One FV for one class may be ideal. Currently, however, there is no such fine classification in the area of voice activity detection.

The invention can take the form of an entirely hardware embodiment, an entirely software embodiment or an embodiment containing both hardware and software elements. In a preferred embodiment, the invention is implemented in software, which includes but is not limited to firmware, resident software, microcode, etc.

Furthermore, the invention can take the form of a computer program product accessible from a computer-readable or computer-readable medium providing program code for use by or in connection with a computer or any instruction execution system. For the purposes of this description, a computer-readable or computer readable medium can be any apparatus that can contain, store, communicate, propagate, or transport the program for use by or in connection with the instruction execution system, apparatus, or device.

The medium can be an electronic, magnetic, optical, electromagnetic, infrared, or semiconductor system (or apparatus or device) or a propagation medium. Examples of a computer-readable medium include a semiconductor or solid state memory, magnetic tape, a removable computer diskette, a random access memory (RAM), a read-only memory (ROM), a rigid magnetic disk and an optical disk. Current examples of optical disks include compact disk-read only memory (CD-ROM), compact disk-read/write (CD-R/W) and DVD.

A data processing system suitable for storing and/or executing program code will include at least one processor coupled directly or indirectly to memory elements through a system bus. The memory elements can include local memory employed during actual execution of the program code, bulk storage, and cache memories which provide temporary storage of at least some program code in order to reduce the number of times code must be retrieved from bulk storage during execution.

Input/output or I/O devices (including but not limited to keyboards, displays, pointing devices, etc.) can be coupled to the system either directly or through intervening I/O controllers. Network adapters may also be coupled to the system to

12

enable the data processing system to become coupled to other data processing systems or remote printers or storage devices through intervening private or public networks. Modems, cable modem and Ethernet cards are just a few of the currently available types of network adapters.

It is appreciated that although embodiments of the invention have been discussed on the assumption that the values for the dynamic weighting coefficient are updated for each frame, this is not obligatory. It is possible to determine values for the weighting factor, for example, in every third frame. The "set of frames" in the appended claims does not necessarily need to refer to a set of frames strictly subsequent to each other. The weighting can be done for more than one frame without losing the precision of class separation. Updating the weighting factor values less often may reduce the accuracy of the voice activity detection, but depending on the application, the accuracy may still be sufficient.

It is appreciated that although in the above description signal to noise ratio has been used as a quality factor reflecting the environment associated with the input signal, other quality factors may additionally or alternatively be applicable.

This description explicitly describes some combinations of the various features discussed herein. It is appreciated that various other combinations are evident to a skilled person studying this description.

In the appended claims a computerized method refers to a method whose steps are performed by a computing system containing a suitable combination of one or more processors, memory means and storage means.

While the foregoing has been with reference to particular embodiments of the invention, it will be appreciated by those skilled in the art that changes in these embodiments may be made without departing from the principles of the invention, the scope of which is defined by the appended claims.

The invention claimed is:

1. A voice activity detection system for discriminating between at least two classes of events, the system comprising:
  - feature vector units for determining at least two different feature vectors for each frame of a set of frames containing an input signal,
  - sets of preclassifiers trained for said at least two classes of events for classifying said at least two different feature vectors,
  - a weighting factor value calculator for determining values for at least one weighting factor based on outputs of said preclassifiers for each of said frames,
  - a combined feature vector calculator for calculating a value for the combined feature vector for each of said frames by applying said at least one weighting factor to said at least two different feature vectors, and
  - a set of classifiers trained for said at least two classes of events for classifying said combined feature vector.

2. The system of 1, comprising thresholds for distances between outputs of said preclassifiers for determining values for said at least one weighting factor.

3. The system of claim 1, wherein each frame of the set of frames comprises overlapping consecutive segments of speech of sizes varying between 10-30 milliseconds.

4. The system of claim 1, wherein the at least two different feature vectors comprise a first feature vector type that is effective in a high signal to noise ratio environment and a second feature vector type that is effective in a noisy environment.

5. The system of claim 1, wherein a select one of the feature vector units comprises:

- a front end that calculates mel frequency cepstral coefficients and their derivatives for each frame, and

13

an acoustic model that receives coefficients from the front end and provides phonetic acoustic likelihoods as a feature vector for each frame.

6. The system of claim 5, wherein the acoustic model comprises a multilingual acoustic model that ensures the usage of a model dependent voice activity detection at least for any of the language for which it has been trained.

7. The system of claim 1, wherein a select set of preclassifiers comprises Gaussian mixture preclassifiers that output Gaussian mixture distributions.

8. The system of claim 1, wherein a select set of preclassifiers comprises a neural network that outputs posterior probabilities of each of the classes.

9. The system of claim 1, wherein a select one of the feature vector units comprises:

a front end that calculates perceptual linear predictive (PLP) coefficients for each frame, and

14

an acoustic model that receives coefficients from the front end and provides phonetic acoustic likelihoods as a feature vector for each frame.

10. The system of claim 9, wherein the acoustic model comprises a multilingual acoustic model that ensures the usage of a model dependent voice activity detection at least for any of the language for which it has been trained.

11. The system of claim 1, wherein a select one of the feature vector units comprises:

an energy band block that provides a feature vector for each frame that relates to the energy of frequency bands.

12. The system of claim 1, wherein the distances comprise at least one of the following: Kullback-Leibler distances, Mahalanobis distances, and Euclidian distances.

13. The system of claim 1, further comprising:

a look-up table that comprises signal to noise ratio class labels and corresponding distances that are calculated between outputs by the preclassifiers in each set.
